UNITED STATES PATENT OFFICE.

JOHN H. HORTON, OF EAST POESTENKILL, NEW YORK.

CAR-COUPING.

SPECIFICATION forming part of Letters Patent No. 231,719, dated August 31, 1880.

Application filed June 17, 1879.

To all whom it may concern:

Be it known that I, JOHN H. HORTON, of East Poestenkill, in the county of Rensselaer and State of New York, have invented certain new and useful Improvements in Car-Couplers; and I do hereby declare the following to be a full, clear, and exact description of the invention, such as will enable others skilled in the art to which it appertains to make and use the same, reference being had to the accompanying drawings, and to letters of reference marked thereon, which form a part of this specification, in which—

Figure 1 represents a top view of two of my improved draw-heads and coupling devices, partly in section; Fig. 2, a sectional view of two of the coupling devices, showing the parts respectively in position for coupling and uncoupling. Fig. 3 represents a detached view 20 of the pawl and its extension, carrying a coupling-pin; Fig. 4, a detached view of the pawl without the extension. Fig. 5 represents a top view of the draw-head, showing the coupling devices arranged in a horizontal position. Fig. 6 represents a side view of the same; and Fig. 7 represents a view, partly in section, of a modification of the coupling devices as arranged when the draw-head is in such position as to allow the coupling devices to work in a 30 horizontal plane.

This invention relates to certain improvements in car-couplers; and it consists in the combination, with a draw-head, of a pawl pivoted in a suitable recess formed in the draw-head for its reception and adapted to operate to automatically drop the coupling-pin into its seat in the draw-head, when two cars are brought together, into and through the coupling-link, the said pawl having attached to it 40 by means of suitable connections a gravitating weight, by means of which the devices can be operated to assist in coupling and uncoupling the cars, the devices being arranged to operate in whatever position the draw-heads 45 may be located.

In the drawings, the letter A indicates the draw-head of a car-coupler, which may be of the ordinary or any approved construction, and which is attached to the car in the usual 50 manner. The letter B indicates an opening in the top, side, or bottom of said draw-head,

leading into the flaring opening or mouth of said draw-head; and C C, the openings for the reception of the coupling-pin, which, when raised from the draw-head, sits with its lower 55 extremity in said opening, and is suitably secured at its upper extremity, so that it will be automatically dropped into the draw-head and through the coupling-link when the pawl C' is tripped by the entrance of said link into the 60 draw-head, as more fully hereinafter specified.

The pivoted pawl at its outer end is provided with an extension, D, slotted on opposite sides and open at its lower end, in which is located the coupling-pin D', which is capable 65 of a back-and-forth motion in said extension, the pin being confined therein by means of a cross-bar, E, extending through the opposite slots, and provided with a confining-wire, F, at its ends, or with confining-pins, as shown; 70 or it may be secured by simply attaching to its ends the ends of the chains O, by which it is elevated to uncouple the cars.

In front of the upper opening C is located a stop, H, which serves to prevent the coupling-pin from being misdirected as the pawl is shifted, and guides it into the upper opening when the cars are coupled. Instead of said stop, however, it is evident that the parts of the draw-head at each side of the upper opening 75 80 may be extended upward, so as to form a guide for said pin to direct it into the upper aperture.

The letters K K represent two screws or bolts passing through the extension of the 85 pawl, which serve to prevent lateral shifting of the pin; and L, a groove formed at the upper edge of the pawl proper, which forms a seat in which the lower part of said coupling-pin rests and is adapted to slide. This groove is 90 not essential, however, and may be dispensed with.

The pawl is secured in place by means of a pivot, M, passing through the walls of the draw-head, and is provided with a segmental 95 groove, which forms a seat for a chain, O, which is secured to a transverse pin, P, at one end, the other end passing through an opening, R, in the draw-head, and being secured to a gravitating weight, R', which is 100 secured to an arm, S, pivoted at T to the draw-head. Said chain and weight serve to

assist in throwing back the pawl when elevating and withdrawing the coupling-pin.

In the modification shown in Figs. 5 and 6 mechanism is illustrated for operating the pawl when the draw-head is in a position other than vertical, in which the letter A' represents one or more chains, to one end of each of which the ends of the cross-bars are connected. Said chain or chains, passing around 10 a suitable pulley or pulleys, C', are secured to the draw-head, and have connected to their lower ends suitable weights D², by means of which the coupling-pin is operated and thrown into its seat in the draw-head when said draw-head is so situated that the pawl and its extension are in a horizontal position.

It is evident that by means of similar pulleys arranged to meet the requirements of the case, and similar chains and weights, provision 20 may be made for throwing the pin into place, whatever may be the position of the draw-head and the pivoted pawl and extension.

In the modification shown in Fig. 7 the extension is provided with a sliding frame, E', 25 which is passed through the opposite ends of the cross-bar E, and is adapted to slide back and forth upon the extension. The chains in this case pass through transverse portions of the draw-head and over the pulley C' on the 30 opposite side.

The operation of my invention will be readily understood in connection with the above description without further explanation.

It is evident that the draw-heads and coupling devices may be precisely alike on opposite cars, or that any description of draw-head and coupling device in which an ordinary coupling-link is employed may be used on the opposite car to which my improved coupling 35 device is attached, by means of which I am enabled to use the device in connection with ordinary trains, which is a matter of great importance. Moreover, it will be seen that as 40

constructed provision is made for securing the draw-bars in any position, so that the pawl 45 and its extension may be in a vertical or horizontal position, or any intermediate position, and worked from above, at one side or below, as may prove most convenient, and also to connect with any height of bumper in ordinary use.

I claim—

1. In combination with the draw-head of a car-coupler, a pawl pivoted therein and provided with a segmental groove, and a chain to 55 which is attached a weight adapted to hold the pawl in a normal position for the insertion of the coupling-pin, substantially as specified.

2. In combination with the draw-head of a car-coupler, a pawl pivoted in an opening in 60 said draw-head and provided with an outward extension, serving as a support and guide to automatically drop the coupling-pin into its seat, substantially as specified.

3. In combination with the draw-head of a 65 car-coupler and the pivoted pawl and its extension and coupling-pin, a stop secured to or formed on the draw-head in front of the upper opening of the coupling-pin, for guiding the pin to its seat in the draw-head, substantially as specified.

4. In combination with the draw-head of a car-coupling, a pawl pivoted in an opening in the draw-head and provided with a rectangular extension and a sliding frame, E', passed 75 through the opposite ends of the cross-bar E, and adapted to slide back and forth upon the extension to operate the coupling-pin, substantially as specified.

In testimony that I claim the foregoing I 80 have hereunto set my hand this 16th day of June, 1879.

JOHN H. HORTON.
